United States Patent Office

Des. 183,113
Patented July 1, 1958

183,113

PLAY AREA ENCLOSURE

Walter W. Bird, Williamsville, N. Y., assignor to Birdair Structures, Inc., Buffalo, N. Y.

Application May 2, 1957, Serial No. 45,989

Term of patent 14 years

(Cl. D13—1)

FIG. 1

FIG. 2

FIG. 3

FIG. 4

FIG. 5

Fig. 1 is a perspective view of a play area enclosure, showing my new design;

Fig. 2 is a top plan view thereof;

Fig. 3 is a side elevational view thereof;

Fig. 4 is an elevational view of one end thereof; and

Fig. 5 is an elevational view of the opposite end thereof.

I claim:

The ornamental design for a play area enclosure, substantially as shown.
